UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed November 13, 1924. Serial No. 749,621.

This invention relates to gages for work-sheets in a typewriting machine, and one of its objects is to provide convenient means for adapting the typewriting machine to different kinds of work.

In many cases it is desired to type the two first lines on a work-sheet in a predetermined position relatively to the leading edge and to the sides of the sheet, and with an unusual space between said lines, as, for example, in typing the date and the address in a letter.

In order to locate the work-sheet so that the first line may be typed thereon, the sheet is inserted down a paper-chute or rear table at the introductory side of the platen and is adjusted forwardly around the platen while being guided and trued by means of the sides or side gages of the paper-chute. Before the first line is typed, the work-sheet is backed up against a bottom-edge gage, which may be adjustably mounted, and the first line may be typed without further attention to the position of the sheet.

After typing the first line, the platen is rotated while the leading edge of the sheet is guided up by a side gage on the delivery side of the platen, and the sheet is thus advanced against a leading-edge gage, which may be adjustably mounted upon a front gage. The second line may now be typed without further attention to the location of the sheet. Upon releasing the leading edge of the work-sheet, the same will spring forwardly, clear of the leading-edge gage, so that new lines may be typed and line-spaced in the usual manner.

The adjustability broadens the scope of work to which the machine may be adapted. The lateral adjustment comprises two side gages which may be slidably mounted upon the intake table.

The bottom-edge gage at the introductory side of the platen, which controls the position of the first line of typing, is particularly advantageous in cases where the first line must be placed relatively near to the leading edge of the sheet, as in such cases the distance between the type of the machine and the leading edge of the sheet is such that it will not permit the lowering of the front gage to meet said leading edge.

Certain features herein disclosed may also be used for the kind of work described in Jesse A. B. Smith's application No. 728,075 filed July 25, 1924, in which it is desired to type at one line upon work-sheets for one class of work, and at a different line of another class of work-sheets.

A feature of the invention relates to a side edge gage for the work-sheet, said gage being provided with a gage adjustably mounted thereon to and away from the platen to locate a work-sheet in a line-space direction around the platen.

Another feature of the invention relates to an L-shaped gage-bar detachably supported on the platen-frame of the typewriter carriage, said gage-bar having a leading-edge gage supported on its vertical leg to position the work-sheet around the platen in a line-space direction, and a side edge gage supported on its horizontal leg to position the work-sheet in a letter-space direction of the platen.

Other features and advantages will hereinafter appear.

In the accompanying drawings,

Figure 1 is a front view, showing the gages, which form the subject of my invention, applied to the platen of a typewriting machine.

Figure 2 illustrates a work-sheet with the first and second lines of writing typed upon it.

Figure 3 is a cross-sectional view, showing the work-sheet around the platen of a typewriting machine in a position for typing upon it the first line of writing, the rear edge of the work-sheet being located against a gage at the introductory side of the platen.

Figure 4 is a cross-sectional view, showing the work-sheet around the platen of a typewriting machine in a position for typing upon it the second line of writing, the leading edge of the work-sheet being located against a gage at the delivery side of the platen.

Figure 5 is a perspective view of a gage mounted to the rear of a typewriting machine for locating the first line of writing in relation to the rear edge of the work-sheet.

Figure 6 is a perspective view of the side

edge gage supported on the horizontal arm of the L-shaped gage-bar at the delivery side of the platen.

A work-sheet 10 is laid flat upon a paper-chute or rear table 11, laterally located by means of side guides 12, is inserted and fed around a platen 13, by means of co-operating pressure rolls 14, in the under side of said platen, and is fed up to a position in front of the platen where a type-bar 15 may strike it while being held in a typing position by a finger 16. The finger-wheel 30, fast on a shaft 31 upon which the platen 13 is mounted, is then turned backward and the work-sheet is backed up against a bottom edge gage 17 adjustably mounted on one of the side guides 12, and the work-sheet is then in a position for typing upon it a first line of typing 28. The gage 17, which forms an integral part of a guiding member 18, is slidably mounted in a slot 19 in the side guides 12, and comprises a screw 20 fast to the member 18, and a finger-nut 21 for binding said gage 17 in a position corresponding to the first line of typing on the work-sheet, as shown in Figures 1 and 3.

In order to position the work-sheet for a second line of typing 29, the platen is rotated while the leading edge of the sheet is held lying on a gage-supporting bar 22, and is fed up to a leading-edge gage 23. The bar 22 is fastened to the machine-frame by means of a bracket 24 and fasteners 25. The gage 23 is adjustably mounted upon the bar 22, and is provided with a binding screw 26 for readily adjusting the gage relatively to the position of the second line of typing on the work-sheet. The bar 22 is fast on the platen-frame of the machine at one side only, extending toward the center of the platen, and is bent upwardly forming a guide on which the gage 23 may be slid.

By releasing the work-sheet it will spring forward to a position shown in dot-and-dash lines in Figure 4, clearing the gage 23, and running tangentially out of the platen 13 at the point where the finger 16 is supporting the work-sheet, and consequently the latter may be fed by means of the regular platen feed for line-spacing, and new lines may be typed upon the work-sheet.

It will be noted that means are provided whereby the gages may be adjusted for readily fitting different classes of work, and for work-sheets of different sizes. The side-guides 12 are laterally adjustable in order that they may be positioned to suit the width of a work-sheet, and are mounted upon a rim 27 formed at the uppermost edge of the paper-chute 11. The uppermost ends of the guides 12 encircle the rim 27 and form a resilient connection rendering the side guides movable into and out of position. The adjustment provided by the gage 17 enables the operative to locate the first line of typ-

ing on the work-sheet, while the adjustment provided by sliding the gage 23 at the delivery side of the platen serves for locating the second line of typing.

It will be understood that the work-sheet may be quickly advanced to the second line by releasing the feed-rolls and then grasping the leading edge and pulling the work-sheet to the leading-edge gage 23, instead of advancing the sheet by means of the platen-rotating knob.

This device may be advantageously used for making entries upon certain classes of work-sheets in which the first line to be typed is a predetermined distance from either the bottom or the leading edge of the sheet. In such cases the gages are adjusted to suit the position of the lines on the sheets, and the entries are made by gaging the sheets by either their bottom or leading edges.

It will further be understood that the two side guides or side edge gages 12 at the introductory side of the platen are comparatively long and form a chute 17^a to square the work-sheet with reference to the platen. When, however, the leading-edge gage 23 is used and set for a line some distance from the top edge of the work-sheet, the bottom edge of the work-sheet may occupy a position well toward the bottom of the chute 17^a, and consequently there may be a tendency for the work-sheet to skew with reference to the platen, due to the short end of the work-sheet remaining in the chute. To guard against this, however, the horizontal arm 22^a of the L-shaped gage-bar is provided with a side edge gage 35 which is adjusted, in alignment with the left-hand side edge gage 12, at the introductory side of the platen, and co-operates therewith to square 105 the work-sheet with reference to the platen. Said side edge gage 35 is provided with a lateral extension or table 36 against which the work-sheet may rest when locating it against said side edge gage. Said side edge 110 gage 35 may be adjusted laterally as well as the side edge gages 12 at the introductory side of the platen, and it may be secured in its adjusted position on said gage-bar by a thumb-screw 37.

The L-shaped gage-bar 22 is detachably supported on the machine, and may be readily applied to any Underwood standard typewriting machine by means of screws 38, which screws ordinarily hold the cover on the end plate of the platen-frame.

Variations may be resorted to within the scope of the invention, and portions of the improvements may be used without others.

Having thus described my invention, I 125 claim:

1. In a typewriting machine, in combination, a platen, releasable feed-rolls therefor; means including a chute and a bottom edge gage at the introductory side of the 130

platens, for locating and truing a work-sheet for the first line of typing, and a leading-edge gage at the delivery side of the platen for positioning the work-sheet for a second line of typing.

2. In a typewriting machine, in combination, a platen, a table at the introductory side of the platen, side gages adjustably mounted on said table, a bottom edge gage for locating a work-sheet for the first line of typing thereon, feed-rolls for feeding the work-sheet around the platen, and a leading-edge gage adjustably mounted at the delivery side of the platen, said last-mentioned gage being effective to locate the work-sheet for a second line of typing thereon.

3. In a typewriting machine, the combination with a platen-frame and a revoluble platen therefor, of a table at the introductory side of said platen, means upon said table for laterally positioning a work-sheet including two side guides adjustably mounted upon said table, and means for engaging the lower end of said work-sheet to position the same for a line of typing, said last-mentioned means including a line-positioning gage adjustably mounted upon one of said side guides and manually-operable means for positioning and locking said gage.

4. In a typewriting machine, the combination with a platen-frame and a revoluble platen therefor, of a table at the introductory side of said platen, means upon said table for laterally positioning a work-sheet including two side guides adjustably mounted upon said table, means for engaging the lower end of said work-sheet to position the same to a line of typing, said last-mentioned means including a line-positioning gage adjustably mounted upon one of said side guides and manually-operable means for positioning and locking said gage, and means at the delivery side of said platen for engaging the leading edge of said work-sheet to position the same to a second line of typing thereon, said last-mentioned means including a side-edge gage fast upon said platen-frame, a second line-positioning gage adjustably mounted thereon and means for locking said second gage.

5. In a typewriting machine, the combination with a platen, of a table at the introductory side of said platen, and side gages mounted thereon for positioning a work-sheet laterally while being introduced around said platen, said side gages being resiliently mounted upon said table for rendering said side gages movable into and out of position, one of said side gages being provided with an elongated slot bearing a stopping device sliding therein, and said stopping device including means for locking the same in any position within the range of the slot in said side gage.

6. In a typewriting machine, the combi-

nation with a platen-frame including two side plates and a platen therefor, of means on said platen-frame for effectively positioning a work-sheet relatively to its leading edge while a line of typing is written thereon, said means including a supporting member fastened to one of said side plates extending parallel to said platen and terminating in a bend and an upwardly-extending portion for carrying a paper-stop slidably mounted thereon, and having means for adjusting and locking the same on the upwardly-extending portion of said supporting member.

7. In a typewriting machine, in combination, a platen, side gages for locating a work-sheet in a letter-space direction of said platen, a bottom edge gage on one of the side gages for locating the work-sheet for a predetermined first line of typing, said bottom edge gage being adjustable to and away from the platen on said side gage, and a leading-edge gage at the delivery side of the platen for positioning the work-sheet for a second line of typing.

8. In a typewriting machine, the combination with a platen, of a side edge gage to locate a work-sheet in a letter-space direction of said platen, a gage on said side edge gage to locate the work-sheet in a line-space direction of the platen, said second-named gage being adjustable to and away from the platen on said first-named gage, said side gage having therein a slot in which the other gage is adjustably supported, and an extension on said other gage to keep the latter from turning in the slot of the side edge gage.

9. In a typewriting machine, in combination, a platen, adjustably-mounted side edge gages at the introductory side of said platen for laterally locating a work-sheet, and a bottom edge gage carried by one of said side edge gages, said last-mentioned gage being effective to locate said work-sheet in a line-space direction around said platen.

10. In a typewriting machine, the combination with a carriage and a platen supported therein, of an L-shaped bar extending in from one end of said carriage, and a work-sheet gage on said bar.

11. In a typewriting machine, the combination with a carriage and a platen supported therein, of an L-shaped bar extending in from one end of said carriage, and a gage adjustably mounted on the vertical leg of said bar.

12. In a typewriting machine, the combination with a carriage and a platen supported therein, of an L-shaped bar extending in from one end of said carriage, and a work-sheet gage on said bar, said bar being detachably mounted on said carriage.

13. In a typewriting machine, the combination with a carriage and a platen sup-

ported therein, of an L-shaped bar extending in from one end of said carriage, and a work-sheet gage on said bar, said carriage comprising a platen-frame, said bar being detachably mounted on the end-plate of said platen-frame.

14. In a typewriting machine, the combination with a carriage and a platen supported therein, of an L-shaped bar extending in from one end of said carriage, a leading-edge gage on said bar, and a side edge gage on the horizontal arm of said L-shaped gage-bar.

15. In a typewriting machine, the combination with a carriage and a platen supported therein, of an L-shaped gage-bar extending in from one end of said carriage, a work-sheet gage on said bar, said gage being adjustable to and away from said platen to locate a work-sheet at various positions in a line-space direction of said platen, and a side edge gage adjustably supported on the horizontal leg of said gage-bar to locate the work-sheet in various positions in a letter-space direction of said platen.

16. In a typewriting machine, the combination with a carriage and a platen supported therein, of an L-shaped bar extending in from one end of said carriage at the delivery side of the platen, a leading-edge

gage on said bar, a side edge gage on the horizontal arm of said L-shaped gage-bar, and a side edge gage at the introductory side of the platen, said last-mentioned side edge gage being in alignment with the side edge gage on said gage-bar.

17. In a typewriting machine, the combination with a carriage and a platen supported therein, of a paper-chute supported on said carriage and associated with said platen, said chute comprising at its ends two side walls by which a work-sheet may be squared with reference to the platen, and a gage in said chute supported on one of its side walls to locate the work-sheet in a line-space direction of said platen.

18. In a typewriting machine, the combination with a carriage and a platen supported therein, of a paper-table at the introductory side of said platen over which a work-sheet may be conducted to said platen, side edge gages on said paper-table to form with the paper-table a chute for said work-sheet, and an adjustable gage on one of said side edge gages to locate the work-sheet in various positions in a line-space direction of said platen according to the adjustment of said adjustable gage.

JOHN WALDHEIM.
